UNITED STATES PATENT OFFICE.

JULIUS ALSBERG, OF NEW YORK, N. Y.

INSULATOR.

1,006,041.

Specification of Letters Patent. Patented Oct. 17, 1911.

Application filed September 28, 1908, Serial No. 455,068. Renewed February 24, 1911. Serial No. 610,602.

To all whom it may concern:

Be it known that I, JULIUS ALSBERG, a citizen of the United States, residing at the city of New York, borough of Manhattan, in the county and State of New York, have invented certain new and useful Improvements in Insulators, of which the following is a full, clear, and exact specification.

My invention relates to means for supporting electrical conductors, and the same has for its object more particularly to provide a simple, efficient and durable insulating support for high-potential electric currents.

Further, said invention has for its object to provide an insulating member proper consisting of flexible insulating material, and a flexible protective inclosure therefor adapted to move laterally in all directions with the insulating member proper.

Further, said invention has for its object to provide an insulator comprising an insulating member proper, and a protective inclosure therefor consisting of a series of independent sections supported one upon the other, and inclosing said insulating member proper.

To the attainment of the aforesaid objects and ends my invention consists in the novel details of construction, and in the combination, connection and arrangement of parts hereinafter more fully described, and then pointed out in the claims.

In the accompanying drawing forming part of this specification I have shown one form of insulator constructed according to and embodying my said invention.

In said drawings 10 designates a horizontal support, and 11 an insulator consisting essentially of strands or filaments composed of a silicon compound, as, for example, spun glass or other substance possessing the characteristics of glass twisted together in the form of a rope or cable 12. One end of said insulating member 12 is spliced thereto adjacent to its end to form a loop 13 in which is disposed an eye 14 adapted to receive a pin 15 secured in the lower bifurcated end of a bolt 16 extending through the support 10 and secured thereto by a nut 17 arranged at the upper end of said bolt. The other or free end of said insulating member 12 is frayed out and secured thereto by cement or other suitable means within a socket 18. 19 denotes an eye provided at the lower end of said socket 18.

adapted to receive an eye 20 of a clamp 21 for carrying a conductor 22.

23 denotes a tubular section having its lower end 24 flared outwardly and provided upon its inner surface, adjacent to the junction of its flared portion with its cylindrical portion, with an inwardly extending shoulder 25 which is adapted to rest upon the upper edge of the socket 18 in order to support said tubular section 23 in position therein and surrounding the lower end of the insulating member 12. The upper end of said tubular section 23 is rounded and provided at its edge with a rounded projecting rim or bead 26, and upon the rounded upper end of said tubular section 23 are supported a series of petticoat insulators 27 27 each consisting of a tubular portion 28 provided at its lower end with an outwardly flaring petticoat 29 in the underside of which is provided a centrally-located socket portion 30 having its base slightly rounded so as to conform to the rounded opposite ends of the tubular sections 23 and 28 of the adjoining protecting sections. The upper end of each tubular section 28 is also slightly rounded and provided with an outwardly extending rounded head or rim 31 conforming in outline and shaped to the sockets 30, 30 of the adjoining protecting sections. The uppermost protecting member 34 is also provided with a petticoat section 29 and at its base with a socket 30 constructed as heretofore described, but the upper or tubular portion of said protecting section 35 is made larger in diameter and provided at its upper end with a recessed portion 36 which is adapted to receive the looped upper end 13 of the insulating member 12 and partly inclose the same, and the lower bifurcated end of the bolt 16 by means of which the insulating member and the protecting sections 23, 27, 34 are supported.

The protecting sections 23, 27, 34 may be made of any suitable material, but by preference of glass, porcelain, or other insulating material, and the protector next below the protector 34 provided upon its inner upper edge with an inwardly projecting rim 105 or bead 31^a to maintain the insulating member 12 properly centered within said protecting sections.

37 denotes a conical hood having a flat portion at its top and secured in position above said insulating member and protecting sections upon the bolt 16 intermediate

- the underside of the support 10 and the collar 38 thereon, and retained in position thereon by means of a nut 17 on the upper end of said bolt 16 above the support 10.
5. It will be noted that in the construction herein shown and described the insulating member or rope 12 is merely secured at its upper end upon the pin 15 extending transversely through the lower end of the bolt 16 and that the individual protecting sections are supported in position and surrounding said rope by means of the lower tubular section 23 which rests upon the socket 18, and that the succeeding superposed protecting sections 27 and 34 are each in turn supported one upon the other so as to be free to move or swing with the insulating member 12 itself, and that the entire insulator with its protective sections is in turn protected by the hood 37 arranged upon the bolt 16 directly below the supporting arm 10.
- Having thus described my invention, what I claim and desire to secure by Letters Patent is:
- 1: An insulator, comprising an insulating member, and tubular protecting means surrounding said insulating member and free therefrom, substantially as specified.
  - 30 2. An insulator comprising an insulating member and a flexible protecting means surrounding said insulating member and free therefrom, substantially as specified.
  - 35 3. An insulator comprising a flexible insulating member, and flexible protecting means surrounding said insulating member and free therefrom, substantially as specified.
  - 40 4. An insulator comprising a flexible insulating member, and a series of tubular protecting sections surrounding said insulating member, substantially as specified.
  - 45 5. An insulator comprising a flexible insulating member, and a series of tubular protecting sections formed of insulating material surrounding said insulating member, substantially as specified.
  - 50 6. An insulator comprising a flexible insulating member, and a series of tubular protecting sections arranged one upon the other and surrounding said insulating member, substantially as specified.
  - 55 7. An insulator comprising a flexible insulating member, means for supporting said insulating member, a series of individual protecting sections arranged one upon the other and forming a flexible protecting member loosely surrounding said insulating member and supported at one end by said insulating member, substantially as specified.
  - 60 8. An insulator comprising a flexible insulating member, means for supporting said insulating member, a series of individual protecting sections formed of insulating material arranged one upon the other and forming a flexible protecting member loosely surrounding said insulating member, substantially as specified.
  - 65 9. An insulator comprising a flexible insulating member, means for supporting said insulating member, a series of individual protecting sections arranged one upon the other and forming a flexible protecting member supported by and loosely surrounding said insulating member, and a hood arranged above said insulating member and protecting members, substantially as specified.
  - 70 10. An insulator comprising a flexible insulating member, means for supporting said insulating member, an attaching device carried by said insulating member, a series of individual protecting sections supported upon said attaching device, and arranged one upon the other and surrounding said insulating member, substantially as specified.
  - 75 11. An insulator comprising a flexible insulating member, means for supporting said insulating member, an attaching device carried by said insulating member, a series of individual protecting sections supported upon said attaching device and arranged one upon the other and surrounding said insulating member, and a hood arranged above said insulating members and protecting sections, substantially as specified.
  - 80 12. An insulator comprising a flexible insulating member, means for supporting said insulating member, an attaching device carried by said insulating member, a series of individual protecting sections arranged one upon the other provided with petticoats, and sockets to receive the opposite ends of adjoining protecting members, substantially as specified.
  - 85 13. An insulator comprising a flexible insulating member, means for supporting said insulating member, an attaching device carried by said insulating member, a series of individual protecting sections arranged one upon the other provided with petticoats and sockets to receive the opposite ends of adjoining protecting members, and a hood arranged above said insulating member and protecting sections, substantially as specified.
  - 90 14. An insulator comprising a flexible insulating member, means for supporting said insulating member, an attaching device carried by said insulating member, a series of individual protecting sections each consisting of a tubular portion and a flaring portion provided at its underside with a socket adapted to receive the tubular portion of an adjoining protecting section and forming a flexible protecting member loosely surrounding said insulating member, substantially as specified.
  - 95 15. An insulator comprising a flexible insulating member, means for supporting said insulating member, an attaching device carried by said insulating member, a series of individual protecting sections each consisting of a tubular portion and a flaring portion provided at its underside with a socket adapted to receive the tubular portion of an adjoining protecting section and forming a flexible protecting member loosely surrounding said insulating member, substantially as specified.
  - 100 16. An insulator comprising a flexible insulating member, means for supporting said insulating member, an attaching device carried by said insulating member, a series of individual protecting sections each consisting of a tubular portion and a flaring portion provided at its underside with a socket adapted to receive the tubular portion of an adjoining protecting section and forming a flexible protecting member loosely surrounding said insulating member, substantially as specified.
  - 105 17. An insulator comprising a flexible insulating member, means for supporting said insulating member, an attaching device carried by said insulating member, a series of individual protecting sections each consisting of a tubular portion and a flaring portion provided at its underside with a socket adapted to receive the tubular portion of an adjoining protecting section and forming a flexible protecting member loosely surrounding said insulating member, substantially as specified.
  - 110 18. An insulator comprising a flexible insulating member, means for supporting said insulating member, an attaching device carried by said insulating member, a series of individual protecting sections each consisting of a tubular portion and a flaring portion provided at its underside with a socket adapted to receive the tubular portion of an adjoining protecting section and forming a flexible protecting member loosely surrounding said insulating member, substantially as specified.
  - 115 19. An insulator comprising a flexible insulating member, means for supporting said insulating member, an attaching device carried by said insulating member, a series of individual protecting sections each consisting of a tubular portion and a flaring portion provided at its underside with a socket adapted to receive the tubular portion of an adjoining protecting section and forming a flexible protecting member loosely surrounding said insulating member, substantially as specified.
  - 120 20. An insulator comprising a flexible insulating member, means for supporting said insulating member, an attaching device carried by said insulating member, a series of individual protecting sections each consisting of a tubular portion and a flaring portion provided at its underside with a socket adapted to receive the tubular portion of an adjoining protecting section and forming a flexible protecting member loosely surrounding said insulating member, substantially as specified.
  - 125 21. An insulator comprising a flexible insulating member, means for supporting said insulating member, an attaching device carried by said insulating member, a series of individual protecting sections each consisting of a tubular portion and a flaring portion provided at its underside with a socket adapted to receive the tubular portion of an adjoining protecting section and forming a flexible protecting member loosely surrounding said insulating member, substantially as specified.
  - 130 22. An insulator comprising a flexible insulating member, means for supporting said insulating member, an attaching device carried by said insulating member, a series of individual protecting sections each consisting of a tubular portion and a flaring portion provided at its underside with a socket adapted to receive the tubular portion of an adjoining protecting section and forming a flexible protecting member loosely surrounding said insulating member, substantially as specified.

15. An insulator comprising a flexible insulating member, means for supporting said insulating member, an attaching device carried by said insulating member, a series of individual protecting sections each consisting of a tubular portion having its upper end rounded and a flaring portion adjacent to its lower end, and a socket provided in the underside of said flaring portion having its base conformed to and adapted to receive the opposite end of a protecting section, means provided upon the lowermost of said protecting sections adapted to engage the attaching device on said insulating member for supporting said superposed series of protecting sections loosely upon and surrounding said insulating member, substantially as specified.
16. An insulator comprising a flexible insulating member, means for supporting said insulating member, an attaching device carried by said insulating member, a series of individual protecting sections each consisting of a tubular portion having its upper end rounded and a flaring portion adjacent to its lower end, a socket provided in the underside of said flaring portion having its base conformed to and adapted to receive the rounded upper end of an adjoining protecting section, and means provided upon the lowermost of said protecting sections for supporting said superposed series of protecting sections upon and loosely surrounding said insulating member, substantially as specified.
17. An insulator comprising a flexible member formed of a silicon compound, an attaching device at the free end thereof, means for supporting said insulating member, a series of individual protecting sections each consisting of a tubular portion having its upper end rounded and provided with a rim, a flaring portion adjacent to its lower end, a socket provided in the underside of said flaring portion having its base conformed to and adapted to receive the opposite end of an adjoining protecting section, means provided upon the lowermost of said protecting sections adapted to engage the attaching device on said insulating member for supporting said superposed series of protecting sections loosely upon and surrounding said insulating member, substantially as specified.
18. An insulator comprising a flexible member formed of a silicon compound, an attaching device at the lower end thereof, means for supporting said insulating member, a series of individual protecting sections each consisting of a tubular portion having its upper end rounded and provided
- with a rim, a flaring portion adjacent to its lower end, a socket provided in the underside of said flaring portion having its base conformed to and adapted to receive the opposite end of a protecting section, means provided upon the lowermost of said protecting sections adapted to engage the attaching device on said insulating member for supporting said superposed series of protecting sections loosely upon and surrounding said insulating member, and a hood arranged above said insulating members and protecting sections, substantially as specified.
19. An insulator comprising an insulating member composed of a cable consisting of strands or filaments of glass, an attaching device at the free end thereof, means for supporting said insulating member, a series of individual protecting sections each consisting of a tubular portion having its upper end rounded and provided with a rim, a flaring portion adjacent to its lower end, a socket provided in the underside of said flaring portion having its base conformed to and adapted to receive the opposite end of an adjoining protecting section, means provided upon the lowermost of said protecting sections adapted to engage the attaching device on said insulating member for supporting said superposed series of protecting sections loosely upon and surrounding said insulating member, substantially as specified.
20. An insulator comprising an insulating member composed of a cable consisting of spun glass, an attaching device at the lower end thereof, means for supporting said insulating member, a series of individual protecting sections each consisting of a tubular portion having its upper end rounded and provided with a rim, a flaring portion adjacent to its lower end, a socket provided in the underside of said flaring portion having its base conformed to and adapted to receive the opposite end of a protecting section, means provided upon the lowermost of said protecting sections adapted to engage the attaching device on said insulating member for supporting said superposed series of protecting sections loosely upon and surrounding said insulating member, substantially as specified.

Signed at the city of New York, in the county and State of New York, this twenty-second day of September, nineteen hundred and eight.

JULIUS ALSBERG.
